PLAYING CARD FOR A GAME

Joseph A. Slais, 425 Shenstone Road, Riverside, Ill.

Filed July 21, 1960, Ser. No. 61,461

Term of patent 14 years

(Cl. D34—5)

Fig. 1.

Fig. 2.

I claim:

The ornamental design for a playing card for a game, substantially as shown.
